Primary Examiner — T Chase Nelson*Assistant Examiner* — Ania Aman(74) *Attorney, Agent, or Firm* — Tucker Ellis LLP; Carlos Garritano(57) **CLAIM**

The ornamental design for a cylinder support system, as shown and described.

DESCRIPTION

FIG. 1 is a perspective view of a cylinder support system showing my new design;

FIG. 2 is a side view of the cylinder support system illustrated in FIG. 1 with the opposite side being a mirror image thereof;

FIG. 3 is a rear view of the cylinder support system illustrated in FIG. 1;

FIG. 4 is a front view of the cylinder support system illustrated in FIG. 1; and,

FIG. 5 is a top view of the cylinder support system illustrated in FIG. 1.

In the drawings, the broken lines depict unclaimed portions of the cylinder support system and form no part of the claimed design.
